UNITED STATES PATENT OFFICE.

GUSTAF T. SWENSON, OF NEAR SAN PEDRO, CALIFORNIA, ASSIGNOR, BY MESNE ASSIGNMENTS, TO PACIFIC WIRELESS TELEGRAPH COMPANY, A CORPORATION OF WASHINGTON.

WIRELESS-TELEGRAPH RECEIVER.

No. 801,118.

Specification of Letters Patent.

Patented Oct. 3, 1905.

Application filed December 1, 1902. Serial No. 133,514.

To all whom it may concern:

Be it known that I, GUSTAF T. SWENSON, a citizen of the United States, residing near San Pedro, in the county of Los Angeles and State 5 of California, have invented new and useful Improvements in Wireless - Telegraph Receivers, of which the following is a specification.

My invention relates to instruments designed for receiving telegraph-messages by the system denominated "wireless telegraphy;" and the object thereof is to produce a simple device which will be operative in all positions and when used in conjunction with a telephone- 15 receiver or other electrically-operated sound-producing instrument will produce therein audible impulses which can be readily understood by the operator and which may be used with a telegraphic receiving instrument.

20 The accompanying drawings, which are diagrammatic representations, illustrate my invention as used in conjunction with a telephone-receiver.

Figure 1 is a diagrammatic view of the 25 whole apparatus. Figs. 2 and 3 are like diagrammatic views with some of the parts enlarged. Fig. 4 shows a modification of the contact between the stationary and moving parts.

30 In the drawings A is a telephone-receiver which is electrically connected by wire B to one pole of battery C and by wire D with ground E or other suitable capacity. The other pole of the battery is electrically connected by wire F to a metallic contact-strip G secured to an insulating-block H, which block is secured to the frame I of a train of wheels J. In the axle K of the outer or slow-est-moving wheel J' of this train is a socket 35 K' in which is mounted a small rod L of polished steel or iron which I will call the "co-herer-rod." It is movable in the socket and is held in any desired position therein by thumb-screw M or by any other suitable 40 means. This train of wheels may be operated by any suitable means which will impart an exceedingly-slow rotary movement to said co-herer-rod. I have shown an electric motor N for that purpose as it imparts a continuous 45 motion which I consider is the best motion.

50 Passing through a threaded hole in contact-strip G is a metallic thumb-screw O having a central socket, (shown in dotted lines,) in

which is longitudinally movable a small metallic rod P to which is centrally secured a 55 carbon filament R which is preferably the size of an incandescent sixteen-candle-power-light carbon. This filament is held pressed against the coherer-rod by pad S affixed to spring T which spring is affixed to rod P thereby preventing any vibratory movement of the filament. By preventing the filament from vibrating all danger is avoided of interfering with the proper flow of the current. When the filament is not thus spring-pressed the vibration thereof often interferes with the flow of the current to such an extent that dashes become dots and the message cannot be properly understood. Rod P is adjustably secured in the socket by the thumb-screw U. The 60 aerial conductor or mast-wire V is electrically connected to wire F; and the frame I is electrically connected by wire W with the ground E or other capacity. In the operation of my device when the telephone-receiver is at the 65 ear of the operator a feeble current flows through the circuit. When the aerial conductor receives the Hertzian waves of the sending instrument more complete contact or cohesion takes place between the carbon fila- 70 ment and the coherer-rod and more current flows from the battery, thereby producing a greater sound in the telephone-receiver, and thereby rendering the electric signals sent by the sending instrument distinctly audible to 75 the operator. The continuous rotation of the coherer-rod, slight as it is, destroys at each 80 interruption of the Hertzian wave the cohesion between the carbon filament and the coherer-rod. If desired the coherer-rod could 85 be made of carbon and the filament replaced by a metallic wire of like capacity, as it is immaterial which part is carbon and which 90 metal. I have also found by experiment that sound is audible in the telephone - receiver 95 when the parts are all metallic but the sound produced is not nearly as distinct as when one of the parts is carbon and the other metal.

In the practical working of my device I have found that a coherer-rod of iron three thirty- 100 seconds of an inch in diameter which is caused to revolve once an hour and a carbon filament taken from a sixteen-candle-power in-candescent-electric-light lamp produced very satisfactory results. I have also found in 105 practice that it is better to change occasion-

ally the engaging surfaces between the carbon filament and the coherer-rod. I am able to make many such changes by reason of the longitudinal movement of the coherer-rod in 5 its socket and the vertical adjustment of the carbon filament. If desired a metallic disk X could be mounted on the end of the shaft on which wheel J' is mounted and the carbon filament held in contact with the disk X.

10 Having described my invention, what I claim as new, and desire to secure by Letters Patent, is—

In a system of wireless telegraphy having

a coherer composed of a stationary carbon filament and a moving contact, means to hold 15 said filament against mechanical vibration comprising a pad affixed to a spring adapted to cause said pad to press said filament against said contact.

In witness that I claim the foregoing I have 20 hereunto subscribed my name this 19th day of November, 1902.

G. T. SWENSON.
